HENRY E. LE GENDRE, OF CRESSKILL, NEW JERSEY, ASSIGNOR TO E. W. BLISS COMPANY, OF BROOKLYN, NEW YORK, A CORPORATION OF WEST VIRGINIA.

DESIGN FOR A PNEUMATIC-TOOL CASING.

40,235.

Specification for Design.

Patented Aug. 24, 1909.

Application filed June 8, 1909. Serial No. 500,967. Term of patent 7 years.

To all whom it may concern:

Be it known that I, HENRY E. LE GENDRE, a citizen of the United States, residing at Cresskill, in the county of Bergen and State of New Jersey, have invented a new, original, and ornamental Design for Pneumatic-Tool Casings, of which the following is a specification, reference being had to the accompanying drawing, forming part thereof, wherein—

Figure 1 is a side elevation. Fig. 2 is a top or plan view of Fig. 1. Fig. 3 is a bottom or under-side view thereof.

The chief feature of the design is the shape of the casing.

I claim:—

The ornamental design for a pneumatic tool casing as shown and described.

In witness whereof, I have hereunto signed my name in the presence of two subscribing witnesses.

HENRY E. LE GENDRE.
